UNITED STATES PATENT OFFICE.

GEORGES CLOETENS, OF BRUSSELS, BELGIUM.

REED-ORGAN.

1,095,268.

Specification of Letters Patent.

Patented May 5, 1914.

Application filed October 7, 1909. Serial No. 521,569.

To all whom it may concern:

Be it known that I, GEORGES CLOETENS, a subject of the King of Belgium, residing at 37 Rue de Lausanne, Brussels, Belgium, have invented certain new and useful Improvements in Reed-Organs, of which the following is a specification.

This invention relates to improvements in wind reed organs employing beating reeds.

One of the objects of the invention is to provide an organ of this kind with a single resonating pipe in place of a plurality of such pipes.

Other objects of the invention will appear from the description which follows.

The accompanying drawings Figures 1 to 4 show an organ constructed according to this improvement. Fig. 1 shows a front elevation of part of an organ partially shown in section. Fig. 2 shows a transverse section on the lines G—H of Fig. 1. Fig. 3 shows a transverse section on the lines I—J of Fig. 1. Fig. 4 shows a transverse section on the lines K—L of Fig. 3. Fig. 5 is a partial section on line A—B, Fig. 3.

The beating reeds 18 are arranged perpendicular to one of the sides of a conical pipe 16, with mouth-piece 17 which is carried by the slide 30, Figs. 1 and 5; these mouth pieces are of any convenient form for affecting the volume of sound issuing therefrom and may be aptly termed "echo-bells."

Fig. 5 is a partial sectional view on line A—B, Fig. 3, showing the slide 30 carrying thereon a plurality of mouth pieces or echo bells 17, a portion of one of each is shown in position in Fig. 1.

The reeds are arranged, as in systems already known, in tubes 19 taking the wind supplied by the tube 20 to a box 21. The sliders 22 perforated with holes permit, as in systems already known, of sounding at will one or another of the stops. A single one of these stops is illustrated in the drawing (see especially Fig. 2.). The longest of the reeds 18 are placed close to the narrowest part of the tube 16. With a stop thus arranged, the same musical effect is obtained as with a series of pipes of different lengths mounted separately upon each one of the reeds. It has been found advantageous to allow the tube 16 to be open at its small end 23. It has moreover been found advantageous to provide the tube 16 with a tube 24 connected to 16 by a central opening 25 and also at each end by the opening 35 at the small end

of the tube 16 and the opening 26 with the large end of the tube 16. It is immaterial whether the opening 35 be arranged to communicate with the tube 16 near its small end as shown in Fig. 1 or with the open air. The auxiliary tube 24 permits the reeds entering the tube 16 in the region of the aperture 25, to vibrate with the same intensity of those which enter into the tube 16 at either end of the said tube. It will be observed that the tube 24 is not for the purpose of modifying the sound but for the purpose of permitting the vibrations of the said reeds to be maintained with the proper intensity. Without this auxiliary tube and its aperture 25 the proper vibrations of the middle reeds would be impossible, due to the inordinate length of the main tube 16.

In the construction illustrated in the drawings there has been given to the tube 16 a cross-section having two flat sides. This arrangement has been adopted because one of these flat sides of the tube 16 facilitates its fitting to the wind box, and the other of these flat sides facilitates the adjustment of the tuning wires 29 of the reeds 18.

In order to be able to alter at will the quality and the intensity of the sound, there is provided toward the large end of the tube 16 a slide 30 bearing various constructions of resonators placed in apertures such as 31 and 32. By moving this slide, one may thus alter the quality of the sound produced by the stop. By adjusting the slide 30 so as to bring its flat part 33 against the large end of the tube 16, it is possible to close this tube almost entirely, whereas it will only be partially closed if against this large end there be moved the hollowed out part 34 of the same slide 30.

Fig. 2 shows diagrammatically the method of controlling the valves 21 by the keys of the instrument, it being understood that any known means might be employed for this purpose. By depressing the key 40, which pivots around the block 41, the connection 42 is raised thereby moving the bell-crank 43 around its pivot 44 so that the connection 45 also attached to said bell-crank will be pulled to the left, thereby moving angularly the other bell-crank 46 to which said connection 45 is attached. The bell-crank 46 imparts a downward movement to the stem 47 of the valve 21 and opens it. When pressure is released from the note, the valve is closed by the spring 48.

Having thus described my invention, I claim:

1. A reed organ comprising a resonating pipe, a plurality of beating reeds of different pitch tuned to form a scale communicating with said pipe, and means for controlling said reeds.
  2. A reed organ comprising a resonating pipe, a plurality of beating reeds communicating with said pipe, selective means for controlling said reeds, and means associated with said pipe to vary the quality of sound produced.
  3. A reed organ comprising a resonating pipe, a plurality of beating reeds of different pitch communicating with said pipe, selective means for controlling said reeds, and means for varying the resonant effect of said pipe.
  4. A reed organ comprising a resonating pipe, a plurality of beating reeds of different pitch communicating with said pipe, selective means for controlling said reeds, a slide arranged to move transversely across one end of said pipe, and a plurality of "echo bells" carried by the slide to be brought into registry with said pipe.
  5. A reed organ comprising a resonating pipe, a plurality of beating reeds communicating with said pipe, selective means for controlling the operation of said reeds, and
- a chamber opening into said pipe and forming an auxiliary passage from one part of said pipe to another part of said pipe.
6. A reed organ comprising a resonating pipe having two flat sides, a plurality of beating reeds provided with tuning wires attached to one of said flat sides with their tuning wires lying against the other flat side, and selective means for controlling the operation of said reeds.
  7. A reed organ comprising a tapered resonating pipe, beating reeds of different length communicating with said pipe, the longer reeds communicating with the narrower part of the pipe and the shorter reeds communicating with the wider part of the pipe, and selective means for controlling the operation of said reeds.
  8. A reed organ comprising a plurality of beating reeds tuned to give a plurality of different notes, selective means to admit pressure wind to said reeds, and a single resonating pipe in communication with all said reeds.

In testimony that I claim the foregoing as my invention, I have signed my name in presence of two subscribing witnesses.

GEORGES CLOETENS.
